APPARATUS FOR INTRODUCING FUEL AD-
JUNCTS INTO INTERNAL COMBUSTION
ENGINES

James H. Gravell, Elkins Park, Pa.

Application June 25, 1931, Serial No. 546,819
Renewed November 4, 1933

3 Claims. (Cl. 123—198)

This invention relates to internal combustion engines and specifically applies to providing an apparatus for introducing fuel adjuncts into the same.

Internal combustion engines, especially those used for propelling automobiles, are prone to the accumulation of carbon or soot in their combustion chambers which, occupying the space allotted to compressed explosive admixtures, causes excessive compression, and results in a "ping" or "knock", which aside from the objectionable noise, interferes with the efficiency of the said engine.

In order to avoid the accumulation of carbon, various fuel adjuncts are introduced into the engine, to remove or prevent the carbon, or, failing in this, to at least silence the "ping". Such substances as water, kerosene, aniline, benzol, alcohol, lead tetraethyl, ammonia, and the like, used singly or collectively, have been proposed for this purpose.

There has been such great difficulty in properly introducing the adjuncts, that only those which can be actually mixed with the fuel prior to carburetion, have found public favor.

The objects of this invention are, to provide an apparatus that will successfully introduce into the engine desired fuel adjuncts in general; to provide such an apparatus that is simple in principle and inexpensive to construct and install, and which will be automatic in action and to generally improve the art of internal combustion engine operation.

The invention is based on my observation that as the throttle of an internal combustion engine is manipulated to control speed or power, the pneumatic pressure in the intake manifold of the engine increases and diminishes and that when a vacuum tank is connected to the said manifold by a conduit, air is exhausted from, and returned to, the tank as the pressure in the manifold falls and rises.

I have further observed that this effect may be used to introduce fuel adjuncts into the engine, but the air exhausted from the vacuum tank must be brought into intimate contact with the adjunct, without disturbing the carburetion of the engine, which, of course, would follow the introduction of uncarbureted air into the intake manifold, or without passing the adjuncts through the carburetor which, being a delicate apparatus might be chemically affected thereby.

In order to commercially accomplish this, I provide an apparatus shown in the single figure of the accompanying drawing.

The single figure of the drawing is a diagrammatic sectional view.

In the drawing, A is a vacuum tank adapted for holding the adjunct B. C is a conduit extending from above the level of the adjunct and communicating with the intake manifold D of an internal combustion engine, such as an automobile engine. To bring the air exhausted from the tank into intimate contact with the adjunct, I provide a wick E extending from the adjunct to the tank terminus of the conduit C. For the purpose of holding the wick in place, I have entered it into the conduit and secured it thereto by a pin G. For filling purposes, I have provided an aperture H which is closed to maintain a vacuum by the screw cap I. J is a suitable washer to assist in maintaining the vacuum. K is the throttle for controlling the explosive charge of the engine; the solid lines show the throttle closed and the dotted lines show the throttle open.

To operate my apparatus, I first fill the vacuum tank A by way of the closable aperture H, up to the liquid level shown at M, with any suitable liquid fuel adjunct, as, for example, an admixture of three parts of ethyl alcohol and one part of 26° ammonia water; all by volume. The opening H is then closed by the screw cap I, thus preventing any air from leaking into my vacuum tank. The adjunct immediately wets the wick E and rises by capillary attraction to that portion of the wick which obstructs the end of the conduit C.

As the throttle K is operated to control the engine, the vacuum in the intake manifold varies from maximum to minimum. When the vacuum increases, as would be the case when the throttle K is closed as shown by the solid lines, air is exhausted from the vacuum tank, through the wetted wick and into the conduit and then to the intake manifold where it mixes with the explosive charge and is carried into the engine. The passage of the air through the wick wetted with the adjunct, enables the air to pick up portions of the adjunct in the form of vapor or spray which are carried with the air into the engine to there produce the desired result.

When the vacuum is decreased in the intake manifold D, which would be the case when the throttle K is opened, as shown by the dotted lines, to increase the speed or power of the engine, air rushes back into the vacuum tank through the conduit C and in so doing is brought into intimate contact with the adjunct by passing through that portion of the wetted wick which obstructs the end of the conduit, thereby absorbing portions

of the adjunct and ready to be exhausted when the throttle is again closed.

The apparatus as shown in the drawing may of course be modified in many respects without departing from the essence of my invention. For instance, the vacuum tank may be mounted at a distance from the intake manifold and the conduit C may be extended by a flexible tube to make connection with the intake manifold; the conduit may enter the tank through the closure for the aperture H instead of entering the tank through the bottom as shown, or the conduit C may even enter the tank through the top. When solid adjuncts are used, the conduit may enter the tank at most any point, in which case air baffles may be the means employed to bring the air exhausted from the tank into intimate contact with the adjunct.

A vacuum tank, having a capacity of about one pint, and when the wick and conduit have a cross-section of about one eighth of a square inch filled with the alcohol-ammonia adjunct, described above, will empty itself in about two hundred miles when employed on the average eight cylinder automobile engine. The adjunct is then renewed from time to time as needs require. I have found the feeding speed of my apparatus depends to a large extent on the cross-section of that portion of the wick obstructing the conduit and on the aperture of the tank end of the conduit C; by making the cross-section of the wick and the diameter of the tank end of the conduit smaller the speed of feeding the adjunct is reduced; hence by proper dimensioning the feeding speed may be regulated to suit requirements. I have found that good results may be accomplished in refilling my vacuum tank every five hundred miles.

I do not intend to be limited in the practice of my invention save as the scope of the prior art and of the attached claims may require.

I claim:

1. Apparatus for introducing fuel adjuncts into an internal combustion engine, said apparatus comprising in combination an intake manifold

for supplying fuel to the engine, a throttle valve controlling the flow of fuel through said manifold, a vacuum tank constructed to hold fuel adjunct and a gas from said fuel adjunct, a conduit extending from said vacuum tank above the level of the fuel adjunct therein to the intake manifold at a point between said throttle and the engine, and a wick in said tank extending into the adjunct therein and into the outlet of said conduit from said tank.

2. Apparatus for introducing fuel adjuncts into and internal combustion engine, said apparatus comprising, in combination, an intake manifold for supplying fuel to the engine, a throttle valve controlling the flow of fuel through said manifold, a vacuum tank constructed to hold fuel adjunct and the vapor of the said fuel adjunct, which tank has but one opening, said opening being above the level of the adjunct therein, a conduit tightly connected to said opening and extending from said opening in the vacuum tank to the intake manifold, to which manifold it is tightly connected at a point between the said throttle and the engine, and means within said tank for equilibrating the vapor exhausted from said tank with the adjunct therein.

3. Apparatus for introducing fuel adjuncts into an internal combustion engine, said apparatus comprising, in combination, an intake manifold for supplying fuel to the engine, a throttle valve controlling the flow of fuel through said manifold, a vacuum tank constructed to hold fuel adjunct and the vapor of the said fuel adjunct, which tank has but one opening, said opening being above the level of the adjunct therein, a conduit tightly connected to said opening and extending from said opening in the vacuum tank to the intake manifold, to which manifold it is tightly connected at a point between the said throttle and the engine, and a wick in said tank and spaced from said manifold for equilibrating the vapor exhausted from said tank with the adjunct therein.
